UNITED STATES PATENT OFFICE.

CASSIUS L. HALL, OF YPSILANTI, MICHIGAN.

MANUALLY-PROPELLED VEHICLE.

1,050,454.

Specification of Letters Patent. Patented Jan. 14, 1912.

Application filed September 25, 1911. Serial No. 651,163

To all whom it may concern:

Be it known that I, CASSIUS L. HALL, a citizen of the United States, residing at Ypsilanti, county of Washtenaw, State of Michigan, have invented a certain new and useful Improvement in Manually-Propelled Vehicles, and declare the following to be a full, clear, and exact description of the same, such as will enable others skilled in the art to which it pertains to make and use the same, reference being had to the accompanying drawings, which form a part of this specification.

My invention relates to manually propelled carriages; it has for its object the production of a carriage primarily designed to be operated by the rider, although some of the details may be employed in power propelled cars without departing from my invention which is described in the following specification and set forth in the claims annexed hereto.

In the drawings:—Fig. 1, is a side elevation of the running gear of my improved car showing the mechanical relation of the various parts with the wheel reduced in size for the purpose of the drawing. Fig. 2, is a partial front elevation showing a front axle and manner of connecting it to the other parts of the running gear. Fig. 3, is a side view of one of the roller clutches with the face plate thereof removed, and Fig. 3^a, is a partial vertical sectional view through Fig. 3. Fig. 4, is a plan view of the structure of the running gear shortened omitting the front axle and its connections. Fig. 5, is a sectional view of Fig. 4 on the line α — α showing the reverse gear out of connection. Fig. 6, is a partially similar sectional view on the line α — α but with the reverse gear engaged.

Similar letters refer to similar parts.

In the drawings, A, represents the main frame; B, the rear axle; C, a sub-frame on which is journaled the rear axle.

D represents the propelling wheel, D¹, the steering wheel.

For convenience of illustrating the operative action of the mechanism, a seat E is shown in Fig. 1, it being obvious that any form of seat or body may be mounted upon the frame, to suit the convenience or desires of the owner.

F, is the front axle, to which are pivoted

at either end, stud axles b, b¹, in the usual manner carrying wheels D¹, D¹.

The oscillation of the lever H³ will actuate the pitman rods K and H² reversely to each other and actuate also any mechanism connected therewith.

The forward axle F, as shown in Fig. 2, has a king bolt of the usual form at F¹, an angular piece of metal F² rests upon the axle F, the kingbolt passing through both but with a loose enough bearing to permit of the oscillation of the curved bar F² in the nature of a bolster of an ordinary construction.

The outer ends of F² are tied together by cross piece F³ completing the bolster and upon which are erected or attached the side bars of the frame A. In the end of the bolster, there are inserted in suitable holes, pins F⁴, F⁴, slidably inserted in holes, in the axle F so that on the oscillation of the axle with reference to the bolster, the pins F⁴, F⁴, are slidable in said holes and prevent the axle F from rotating around the king bolt F¹ as is the case in the ordinary fifth wheel.

The driving mechanism is of peculiar construction as already intimated; the rear axle

is journaled in a sub-frame C and not upon the main frame A. This frame C is by virtue of clasps C³ slidably held to the main

frame A having a small endwise movement in relation thereto for a purpose hereinafter described. This endwise movement is controlled by a center cam C⁴ located in a plate

C⁵ extending from side to side and firmly attached to the front ends of the sub-frame C. Joining the main frame A is also a plate or bar C⁶ forming a part of the cam; attached to the cam is an arm C⁷ shown in dotted lines underneath the plate and a

reach rod C⁸ which is connected to a lever C⁹ within easy reach of the operator. By

rotating the cam C⁴ in the larger opening in the plate C⁵, the frame C may be moved endwise with reference to the main frame A to

the extent of the cam movement and rigidly held in either the forward or rearward position.

By this means, it is obvious that the distance between the front axle and the rear axle may be relatively lengthened or shortened by the movement of the sub-frame with reference to the main frame.

The rear end of the sub-frame C is held to the main frame A by a pair of angular le-

vers L_1, L_2 . At the angular part of the levers L_1, L_2 , they are pivoted to the main frame at L^4 , (see Figs. 5 and 6). The lower slotted end of the lever L_1 is pivoted to the sub-frame at L^2 ; in the upper ends of the levers L_1, L_2 , is journaled a shaft L^8 . This shaft carries a spur pinion L^4 . The axle B carries a spur pinion L^5 . A shaft L^6 journaled at L^4, L^5 upon the main frame carries firmly attached thereto a driving gear L^8 . When the frame C is thrown forward with reference to the frame A drawing thereby the rear axle up toward the driving gear L^8 , the pinion L^4 engages in the spur wheel L^8 , as shown in Fig. 5. By virtue of the action of the two angular levers L_1, L_2 , at the same instant, the spur pinion L^4 is thrown upwardly and rearwardly and if previously in engagement with the driving gear L^8 is thrown out therefrom and also if previously in engagement with the spur pinion L^5 , as shown in Fig. 6, it is thrown away and out of engagement from the pinion L^5 , as shown in Fig. 5.

When the sub-frame C is shifted to the rear carrying the rear axle and the pinion L^5 with it, with reference to the main frame A as shown in Fig. 6, the action of the angular levers L_1, L_2 , is to throw the shaft L^8 forward, the spur pinion L^4 into engagement with the driving gear L^8 and simultaneously into engagement with the spur pinion L^5 . These motions are so timed that the spur pinion L^4 does not engage with the gear L^8 and the pinion L^5 until after the wheel L^8 is disengaged from the driving gear L^8 and therefore there is no clashing or contraction of the gears. It is obvious that given a movement of the gear L^8 , as shown in the direction of the arrow, that when the pinion L^4 is engaged with L^8 and also with L^5 , that the direction of rotation of the pinion L^4 and therefore of the rear axle must be contrary to what it would be if the pinion L^5 was directly engaged with the gear L^8 ; in other words, the arrangement is a reverse gear and while it is not new or novel to throw in an idler gear and disengage a direct gear, the manner in which this is performed in this structure and especially, in disengaging the wheel L^8 so that it is not engaged with either the pinion or the driving wheel L^8 , I claim is distinctly new, as while the direct drive is employed, the idler pinion so-called, is never rotated but is out of engagement entirely. This result is effected by the angularity of the bent levers L_1, L_2 , and the manner in which they are actuated, it being obvious from inspection that the swing of the upper arm of said lever upon the pivot L^4 would not only withdraw L^4 from engagement with the wheel L^8 but would also lift it out from engagement with the pinion L^5 .

The spur pinion L^4 may be mounted upon the usual compensating gear, but in car-

riages of this type, it is hardly necessary to drive both driving wheels through the means of a compensating gear and usually but one wheel is intended as a driving wheel, the other running loosely upon the axle. 70

I have shown in Fig. 4, means for engaging the driving wheel with the axle B by means of the jaw clutch B^2 , a yoke lever B^3 , a reach rod B^5 which may be carried to the driver's seat and actuated in any convenient manner. A spring S normally holds the clutch B^2 into engagement with the wheel W . There is nothing new in this construction and therefore it is not necessary to describe it with any degree of particularity. 80

Upon the axle B is mounted a brake drum B^6 with a brake band and detachments for actuating the same, but as this is also common and contains nothing new, I do not deem it necessary to describe it in detail, as such description not only requires a multiplicity of words, but complexity of drawings. 85

Mounted upon the axle L^6 are two preferably ball or roller clutches M, M' , shown more particularly in detail in Figs. 3 and 3^a. These clutches in themselves are not new, they consist of an interior disk having angular notches therein, in which are located rollers which are held in position by an annular ring and plate cover M^3 , to which is firmly attached an arm M^4 .

The pitman rod H^8 extends from that portion of the lever or steering post H^3 in Fig. 1, shown below the pivoting of the lever, to the arm M^4 . The pitman rod K runs angularly and is connected to the lower end of a similar arm of the clutch M and to the lever H^3 above the pivotal mounting. 100

The oscillation of the manually operated lever H^3 alternately moves the arms, attached to the clutch plates, forward and they are, therefore, always moving in an opposite direction to each other. In their forward movement, the clutch plate catches 105 the other portion of the clutch and rotates it. In the movement backward, the clutch plate slides over the other portion of the clutch and does not actuate it. This is due to the construction of the clutch which is shown in the drawings as a ball-clutch and, it being a well known form of construction, it is not illustrated in detail or described specifically; in fact, any other arrangement of clutch or ratchet by which the impulses 110 would be communicated only when passing in one direction would be suitable. It will be noted from Fig. 1, that the arms, attached to the clutch, (one of which is indicated as M^4) are both on the same side of 115 the sub-frame and are both comparatively long. By placing them on the same side of the sub-frame and below it is possible to give them considerable length. By connecting up the pitman rods on opposite sides of 120

the pivotal mounting of the lever H^3 it is possible to place them on the same side of the sub-frame C.

Comparatively long arms for actuating the driving wheels give an increased leverage for furnishing the hand power to the driving wheel. This is a very desirable result, inasmuch as it makes the oscillation of the lever H^3 considerably easier and considerable less strength in the child to drive the vehicle, is required.

It is obvious by moving the sliding frame only a part of its range of movement, say about one-half thereof, that both pinions would be disengaged from the propelling wheel H^3 and therefore the power would be entirely cut off from the propelling wheel and the car could be left to coast under the control of the brake.

20 What I claim is:—

1. A manually propelled vehicle, having in combination, a vehicle body carrying front and rear wheels, a pair of clutches for driving the wheels, a pivotally mounted lever, comparatively long arms one depending on the under side from the actuating clutch part of each clutch and pitman rods connecting the long arms with the lever, one rod below and the other rod above the pivotal mounting of the lever, whereby a large leverage can be secured without interfering with other parts, substantially as described.

2. In a carriage, the combination of a frame, a sub-frame slideable with respect thereto, a driving gear carried by the frame, a driven axle located on the sub-frame, an angular lever linking the sub-frame and frame together, a spur pinion carried on the end of said lever, a second spur pinion carried by the driven axle, and means for shifting the frames relatively to engage the spur pinion on the driven axle with the driving gear and to disengage it therefrom or engage the spur pinion on the end of the angular lever with both the driving gear and the other spur pinion or disengage it from both the driving gear and spur pinion, substantially as described.

3. In a carriage, the combination of a frame, a sub-frame slideable with respect thereto, a driving gear carried by the frame, a driven axle located on the sub-frame, an angular lever linking the sub-frame and frame together, a spur pinion carried on the

end of said lever, a second spur pinion carried by the driven axle, a cam plate attached to the frame and provided with an opening, a cam carried by the sub-frame and means for revolving the cam in the opening of the cam plate, so as to shift the frame relatively to engage the spur pinion on the driven axle with the driving gear and to disengage it therefrom or engage the spur pinion on the end of the angular lever with both the driving gear and the other spur pinion or disengage it from both driving gear and spur pinion, substantially as described.

4. A manually propelled vehicle, having in combination, a vehicle body carrying front and rear wheels, a pair of clutches arranged to actuate the wheels when each is forwardly actuated, a pivotally mounted lever, an arm depending from the actuating clutch part of each clutch and pitman rods connecting the clutch arms with the pivotally mounted lever, one rod below and the other rod above the pivotal mounting of the lever, whereby the vehicle is driven wholly by the draft upon the clutch arms, substantially as described.

5. A manually propelled vehicle, having in combination, a vehicle body carrying front and rear wheels, a pivotally mounted lever, a pair of clutch parts whose rotation rotates the wheels, a second pair of clutch parts for actuating the first mentioned pair of clutch parts, the said clutch parts being all arranged so that the actuated clutch parts are only operated when the companion actuating clutch parts are moved in one direction, comparatively long arms depending from the actuating clutch part of each clutch, and pitman rods connecting the clutch arms with the pivotally mounted lever, one pitman rod below and the other pitman rod above the pivotal mounting of said lever, whereby the vehicle may be driven wholly by draft upon the clutch arm and w' creby increased leverage is secured by the length and location of the clutch arm, substantially as described.

In testimony whereof, I sign this specification in the presence of two witnesses.
